UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING-MACHINE.

1,395,996.

Specification of Letters Patent.

Patented Nov. 1, 1921.

Application filed May 23, 1918, Serial No. 236,225. Renewed March 30, 1921. Serial No. 457,028.

To all whom it may concern:

Be it known that I, MORRIS P. HOLMES, a citizen of the United States, residing at Claremont, in the county of Sullivan and 5 State of New Hampshire, have invented certain new and useful Improvements in Mining-Machines, of which the following is a full, clear, and exact specification.

My invention relates to mining machines. 10 It has heretofore been proposed to angle a short-wall mining machine relative to the face in such a manner as, for instance, to enable the same to pass directly from its sumping cut to its transverse cutting position by means of a double reeve connection 15 extending from the rear end of the machine around a guide at the rib and back to the rear end of the machine.

My invention has for its object to provide 20 an improved feed controlling mechanism for such a machine, which is effective to enable the machine to be controlled in the desired manner. A further object of my invention is to provide improved and simplified feed 25 controlling means which, while not limited thereto, is adapted to use in connection with a standard machine of the type utilizing a chain as a feeding member. Other objects and advantages of my improved construction 30 will, however, hereinafter more fully appear.

In the accompanying drawings I have shown for purposes of illustration one embodiment which my invention may assume 35 in practice.

In these drawings,

Figure 1 is a plan view of a mining machine equipped with my improvement.

Fig. 2 is a detail sectional view of the 40 illustrative clamping means.

Fig. 3 is a diagrammatic view showing the machine after the completion of its sumping cut and ready to begin its transverse cut.

45 Fig. 4 is a similar diagrammatic view showing the machine and its connections when the machine is making its transverse cut.

Fig. 5 is a similar diagrammatic view 50 showing the machine and its connections after the completion of its transverse cut.

and when the same is ready to be withdrawn from the face.

In this illustrative construction, I have shown my invention as applied to use in connection with a standard form of short-wall mining machine including a frame 1 having a forwardly projecting cutter bar 2 and a cutter chain 3 movable about the bar and driven through suitable driving mechanism from a motor 4 carried on the frame. As usual in such constructions, it will be observed that a feed driving member 5 located at the rear end of the machine is also operatively connected to the motor 4 through mechanism, not shown, and that flexible feeding connections, herein shown in the form of a flexible feeding chain 6 disposed as usual around coöperating idler sprockets 7 and 8, are provided to feed the machine during its cutting operations. As the specific construction of the machine, however, does not enter into the present invention, it is believed that a more detailed description of the same is accord- 75 ingly unnecessary.

In my improved construction it will be observed that while one end of the flexible feeding member or chain 6 is connected in the usual manner to a jack 9 located at the 80 left hand rib, the end of the same extending to the right hand rib is extended around a guide sprocket or sheave 10, preferably disposed in a horizontal plane and mounted on a suitable fixed support 11, herein shown to be fixed to the rib at the point usually occupied by the jack, although it may obviously be held in fixed position by any other well known means. As shown, this member 10 is also provided with ratchet 90 teeth 12 around its periphery and a coöperating pawl 13 pivoted at 14 on the member 11 and normally depressed by a spring 15. Around this member, as shown, the end of the chain 6 is carried and then directed 95 back toward the machine frame to which it is adjustably connected through a suitable clamping mechanism hereinafter described, its extremity being preferably removably attached, as by a hook 16, to another flexible 100 member forming a continuation of the feed chain, herein shown in the form of a cable.

17, which extends between suitable gripping surfaces 18 formed on coöperating gripping members 19 and 20 fixed to the frame 1 at a point adjacent its rear end, as shown. Obviously, these members 19 and 20 may be brought into clamping relation by any desired means, but it will be noted that herein I have shown the same controlled by means of a suitable hand lever 21 operatively connected to a cam member 22, which in turn coöperates with a coöperating cam member 23 carried on a pin 24.

In considering the operation of my improved construction, let us refer to Figs. 3, 15 4, and 5. In Fig. 3 it will be noted that after the machine has completed its sumping cut shown therein, the cable 17 is drawn through the clamping members 19 and 20 until the end of the chain is relatively close 20 to the machine. Then the clamp is set. As a result, when the driving member 5 is started, the rear end of the machine moves away from the rib at approximately a third the speed of movement of the front end of 25 the bar, as the latter swings through its arc toward its normal transverse cutting position. Obviously when the machine has reached this position it will then only be necessary to release the clamping members 30 19 and 20 in order to eliminate the retarding action of the rear end of the machine, through the insertion of sufficient slack in the reeve of the feeding member extending between the sheave and the clamping means. 35 It will also be evident that, due to the provision of the pawl 13, while the latter will enable the chain to be drawn therethrough as may be necessary during the angling operation, this pawl will, as soon as the clamp 40 is released, then actively engage the chain in such a manner as to coöperate therewith in forming a fixed abutment. In other words, it will be observed that while the pawl is inoperative during the initial angling movement of the machine, it becomes 45 automatically operative as soon as the clamp is released, so that the machine may operate during its transverse cut in the same manner as any standard machine of the type utilizing 50 a continuous flexible feeding member. In the use of my improved construction, it will also be observed that at any time thereafter or after the machine has completed its transverse cut, as shown in Fig. 5, it is 55 only necessary for the clamping means 19, 20 to be again adjusted into clamping position in order to enable the machine to be angled around an obstruction or withdrawn from the cut and backed over to the right 60 hand rib in the desired manner.

As a result of my improvement it will be observed that a machine of standard construction may be adapted to the desired refinements of control indicated above with-

out any material addition thereto, the only 65 mechanism necessary to be applied to the machine being the clamping means 19, 20 and the controlling means therefor, which may, and preferably do, form a unit adapted to be attached to the rear end of the machine. So far as concerns the coöperating means at the right hand rib, it will also be observed that here it is only necessary to provide an exceedingly simple mechanism, as distinguished from the take-up mechanism which has heretofore been necessary. These and other advantages of my improved construction will, however, be clearly apparent 75 to those skilled in the art.

While I have in this application specifically described one embodiment which my invention may assume in practice, it will be understood that this form is shown for illustrative purposes only and that the invention may be modified and embodied in various 80 other forms without departing from its spirit or the scope of the appended claims.

What I claim as new and desire to secure by Letters Patent is:

1. In a mining machine, a frame having 90 a cutter bar projecting therefrom, feeding mechanism therefor including a flexible feeding member disposed in front and rear thereof, a fixed guiding member around which the rear end of said feeding member 95 is directed back toward said frame, and an adjustable clamp on the rear end of said frame controlling the movement of said feeding member.

2. In a mining machine, a frame having 100 a cutter bar projecting therefrom, feeding mechanism therefor including a feed chain disposed in front and rear thereof, a fixed guiding member around which the rear end of said feed chain is directed back toward 105 said frame, and means including an adjustable clamp on the rear end of said frame controlling the movement of said feed chain.

3. In a mining machine, a frame having 110 a cutter bar projecting therefrom, flexible feeding means therefor including a member having a portion extending rearward and back toward the rear end of said frame, means on said frame for varying the length of said portion, guiding means around which said portion extends, and automatically acting controlling means controlling the movement of said portion relative to said guiding means.

4. In a mining machine, a frame having 120 a cutter bar projecting therefrom, flexible feeding means therefor including a member having a portion extending rearward and back toward the rear end of said frame, means on said frame for varying the length 125 of said portion, guiding means around which said portion extends, and automatically acting controlling means for interrupting the

- movement of said portion relative to said guiding means.
5. In a mining machine, a frame having a cutter bar projecting therefrom, flexible feeding mechanism thereon including a member having a portion extending rearward and back toward the rear end of said frame, means on the frame for varying the length of said portion, guiding means around which said portion extends, and automatically acting controlling means controlled by the movement of said portion relative to said guiding means.
6. In a mining machine, a frame having a cutter bar projecting therefrom, flexible feeding means therefor including a member having a portion extending rearward and back toward the rear end of said frame, means on said frame for varying the length of said portion, guiding means around which said portion extends, and automatically acting controlling mechanism for interrupting movement in one direction of said portion relative to said guiding means.
7. In a mining machine, a frame having a cutter bar projecting therefrom, feeding mechanism therefor including a feed chain having a portion extending rearward and back toward the rear end of said frame, means on said frame for varying the length of said portion, guiding means around which said portion extends, and automatically acting ratchet mechanism controlling the movement of said portion relative to said guiding means.
8. In a mining machine, a frame having a cutter bar projecting therefrom, flexible feeding means therefor including a member having a portion extending rearward and back toward the rear end of said frame, guiding means around which said portion extends, a flexible connection forming a continuation of said member and between said portion and the rear end of said frame, and clamping means carried on the rear end of said frame and relative to which said flexible connection is slidable at will.
9. In a mining machine, a frame having a cutter bar projecting therefrom, flexible feeding means therefor including a feed chain having a portion extending rearward and back toward the rear end of said frame, guiding means around which said portion extends, a flexible connection between said feed chain and the rear end of said frame removably connected to said chain, and clamping means on the rear end of said frame relative to which said flexible connection is slidable.
10. In a mining machine, a frame having a cutter bar projecting therefrom, flexible feeding means therefor including a member having a portion extending rearward and back toward the rear end of said frame, fixed rearwardly located guiding means 65 around which said portion extends, automatically acting mechanism controlled by movement of said member for interrupting movement thereof in one direction, and cooperating controlling means on the rear end 70 of said frame.
11. In a mining machine, a frame having a cutter bar projecting therefrom, flexible feeding means therefor including a feed chain having a portion extending rearward 75 and back toward the rear end of said frame, a flexible connection between said feed chain and the rear end of said frame removably connected to said chain, clamping means on the rear end of said frame relative to which 80 said flexible connection is slidable, guiding means around which said portion extends, and automatically acting ratchet mechanism controlling the movement of said portion relative to said guiding means. 85
12. In a mining machine, a frame having a cutter bar projecting therefrom, feeding mechanism therefor including a flexible feeding member disposed in front and rear thereof, a fixed guiding member around 90 which the rear end of said feeding member is directed back toward said frame, and means on said frame operative to adjustably control the free length of said backwardly directed portion, said means being constructed and arranged to permit said backwardly directed portion to extend in straight line therefrom to said fixed guiding member. 95
13. In a mining machine, a frame having a cutter bar projecting therefrom, feeding 100 mechanism therefor including a flexible feeding member disposed in front and rear thereof, a fixed guiding member around which the rear end of said feeding member is directed back toward the frame, and 105 means on the rear end of said frame and manually controllable to adjustably control the free length of said backwardly directed portion, said means being constructed and arranged to permit said backwardly directed 110 portion to extend in a straight line therefrom to said fixed guiding member.
14. In a mining machine, a frame having a cutter bar projecting therefrom, flexible feeding means therefor including a member having a portion disposed in front thereof and a portion disposed in the rear thereof, said last mentioned portion being carried back toward the rear end of said frame, means on the frame for varying the length 115 of said last mentioned portion, fixed guiding means around which said portion extends, and means operative to automatically limit the rate of movement of the rear end of the machine to a rate not in excess 120 of that of the forward end thereof. 125
15. In a mining machine, a frame having a cutter bar projecting therefrom, feed-

ing mechanism therefor including a flexible feeding member disposed in front and rear thereof, a fixed guiding member, the portion in rear of said frame passing around 5 said fixed guiding member and extending back toward the rear end of said frame, and a plurality of means controlling the rate of

movement of the rear end of said machine including manually adjustable means and automatic means for limiting the rate of 10 movement to a predetermined maximum.

In testimony whereof I affix my signature.

MORRIS P. HOLMES.
